United States Patent Office

Des. 198,680
Patented July 21, 1964

198,680

TABLET COUNTING TRAY

Robert J. Waller, 655 N. Hill St., Pasadena, Calif.

Filed Jan. 17, 1964, Ser. No. 78,244

Term of patent 14 years

(Cl. D16—1)

FIG. 4

FIG. 5

FIG. 6

FIG. 7

FIG. 8

FIG. 1 is an isometric view of a tablet counting tray showing my new design;

FIG. 2 is a top plan view thereof;

FIG. 3 is an elevation as seen from the front side of FIG. 1;

FIG. 4 is an elevation as seen from the rear side of FIG. 1;

FIG. 5 is an elevation as seen from the left of FIG. 4;

FIG. 6 is an elevation as seen from the right side of FIG. 4;

FIG. 7 is a bottom plan view; and

FIG. 8 is a fragmentary sectional view on line 8-8 of FIG. 2.

I claim:

The ornamental design for a tablet counting tray, substantially as shown.
